UNITED STATES PATENT OFFICE.

ALLEN A. TIRRELL, OF PITTSBURGH, PENNSYLVANIA, ASSIGNOR TO WESTINGHOUSE ELECTRIC AND MANUFACTURING COMPANY, A CORPORATION OF PENNSYLVANIA.

PIVOTAL MOUNTING.

1,392,234.

Specification of Letters Patent. Patented Sept. 27, 1921.

Application filed August 11, 1917. Serial No. 185,793.

To all whom it may concern:

Be it known that I, ALLEN A. TIRRELL, a citizen of the United States, and a resident of Pittsburgh, in the county of Allegheny and State of Pennsylvania, have invented a new and useful Improvement in Pivotal Mountings, of which the following is a specification.

My invention relates to pivotal mountings for vibratory members, such as the armatures of electrical relays and similar devices, and it has for its object to provide a durable and economical pivotal mounting for such members.

Considerable difficulty has heretofore been experienced with the pivot pins and bearings of the armatures of electrical relays and similar devices on account of wear resulting from rapid and continuous vibration of the armatures. Frequent renewal and adjustment of the parts has accordingly been required, and it is the object of the present invention to provide a mounting which shall not be subject to wear and shall, therefore, not require replacement and adjustment of the parts.

My invention is illustrated in the accompanying drawing, Figure 1 of which is a view, in side elevation, of an electrical relay embodying my invention; Fig. 2 is a side view of the armature and its mounting; Fig. 3 is a plan view of the armature and its mounting, and Fig. 4 is an end view of the same parts.

My invention is illustrated as employed in connection with an electrical relay comprising a base member 1 which supports the remaining parts, including a U-shaped magnetizable core 2 the legs of which are surrounded by energizing coils 3 and the ends of the legs of which are located adjacent to a flat armature member 4. Attached to one end of the armature 4 is a cross piece 5 that is provided, at each end, with two seats arranged at right angles to each other for the reception of plate springs 6 and 7 that are riveted, or otherwise attached thereto, the springs 6 crossing the springs 7 adjacent to the cross-piece 5 and at approximately the pivotal axis of the armature. The upper ends of the springs 6 are secured to the base portion of a bracket 8 which is, in turn, secured to the base member 1 by means of tap screws 9, the bracket having downwardly

and laterally extending arms to the lower ends of which the springs 7 are riveted or otherwise attached.

The mounting of the armature is such that its vibratory movement occurs around a pivotal axis located approximately on the line of intersection of the planes of the plate springs 6 and 7, and the location of this pivotal axis is substantially invariable because the only movement permitted by the plate springs is that which tends to subject the springs to a bending moment. The springs not only serve as a pivotal mounting but may also be employed to maintain, or to assist in maintaining, the armature normally out of engagement with the poles of the electromagnet. The movements of the armature are so slight that the springs do not become fatigued in service and the mounting is, therefore, not subject to wear and is permanent.

While my invention is illustrated as employed in connection with the armature of an electrical relay, it is obvious that it may be employed in other relations and for other purposes, and I desire also to have it understood that the invention is not limited in its scope to the specific details of construction illustrated and described.

I claim as my invention:

1. The combination with a movable member, of a pivotal mounting therefor comprising pairs of crossed resilient members located to vibrate in parallel planes and each plate having one end rigidly attached to the same end of the movable member, and stationary parts to which the other ends of the resilient members are attached, whereby the movable member may effect a movement of rotation relative to the stationary parts.

2. The combination with a movable member, of a pivotal mounting therefor comprising crossed resilient members each having one end rigidly attached to the movable member adjacent to one end of the pivotal axis, and stationary parts remote from the pivotal axis to which the other ends of the resilient members are rigidly attached.

3. The combination with a movable member, of a pivotal mounting therefor comprising pairs of resilient members each having one end rigidly attached to same end of the movable member and crossing each other at approximately the pivotal axis of the mov-

able member, and stationary parts to which the other ends of the resilient members are rigidly attached.

4. The combination with a movable member, of a pivotal mounting therefor comprising pairs of plate springs located in parallel planes, the springs of each pair of plate springs intersecting each other and each spring having one end rigidly attached 10 to the same end of the movable member, and stationary parts to which the other ends of the springs are rigidly attached, whereby the movable member may effect a movement of rotation relative to the stationary parts.
5. The combination with a movable member, of a pivotal mounting therefor comprising pairs of metal plates arranged to vibrate in parallel planes with their planes intersecting each other and each having one end 20 rigidly attached to the same end of the movable member, and stationary parts to which the other ends of the plates are attached, whereby the movable member may effect a movement of rotation relative to the stationary parts.

6. The combination with a movable member, of a pivotal mounting therefor com-

prising a cross-piece upon the movable member, a pair of metal plates at each end of the cross-piece arranged with their planes 30 intersecting each other and each plate having one end attached to the cross-piece, and a bracket to which the other ends of the plates are attached.

7. In an electromagnet, the combination 35 comprising a supporting frame, an armature and means for pivotally mounting the armature on said frame, said mounting comprising crossed resilient members, the respective ends of said members being attached to one end of the armature and to the supporting frame.

8. In an electromagnet, the combination with an armature, of a pivotal mounting therefor comprising plate springs arranged 45 with their planes intersecting each other and each having one end attached to the armature, and a frame to which the other ends of the springs are attached.

In testimony whereof, I have hereunto 50 subscribed my name this 3rd day of August 1917.

ALLEN A. TIRRILL.

It is hereby certified that in Letters Patent No. 1,392,234, granted September 27, 1921, upon the application of Allen A. Tirrill, of Pittsburgh, Pennsylvania, for an improvement in "Pivotal Mountings," errors appear in the printed specification requiring correction as follows: Page 1, line 89, claim 1, strike out the word "plate"; page 2, line 19, claim 5, after the word "each," second occurrence, insert the word *plate*; and that the said Letters Patent should be read with these corrections therein that the same may conform to the record of the case in the Patent Office.

Signed and sealed this 29th day of November, A. D., 1921.

[SEAL.]

KARL FENNING,
Acting Commissioner of Patents.
